SKIVING MACHINE

Paul H. Dixon, Wenham, Mass., assignor to United
Shoe Machinery Corporation, Flemington, N. J.,
a corporation of New Jersey

Application November 25, 1941, Serial No. 420,399

9 Claims. (Cl. 69—16)

This invention relates to skiving machines and is herein illustrated and described as embodied in a skiving machine of the type disclosed in United States Letters Patent No. 2,041,701, granted May 26, 1936, upon the application of Milton H. Roske, and also in United States Letters Patent No. 2,134,809, granted November 1, 1938, upon the application of Charles C. Bell. The illustrated skiving machine, like those disclosed in the above-mentioned patents, is provided with a driven feed roll, a feed disk having its axis at right angles to the axis of the roll and arranged to press a work-piece against the roll, and a rotary disk skiving knife.

It is an object of the present invention to provide an improved skiving machine of the type above referred to. In accordance with a feature of the invention, the feed disk is arranged to yield in a plane normal to its axis. Regardless, therefore, of the thickness of a work-piece, the feed disk is not displaced axially and hence cannot jam against the rotary knife. This renders frequent axial adjustment of the position of the feed disk unnecessary, even if work-pieces of different thicknesses are to be operated upon. Furthermore, it permits a relatively close adjustment between the feed disk and the knife without danger of jamming as a result of local inequalities of thickness of a work-piece.

These and other features of the invention will be described as embodied in an illustrative machine and pointed out in the appended claims.

Referring now to the accompanying drawings, Fig. 1 is a front elevation of the illustrative machine;

Fig. 2 is a front elevation of the work feeding and gaging mechanism of the machine;

Fig. 3 is a rear elevation of the mechanism for adjusting the edge gage;

Fig. 4 is a perspective view of the feed disk and its support;

Fig. 5 is a plan view in section taken slightly above the element 108;

Fig. 6 is an elevation of the members shown in Fig. 5;

Fig. 7 is an enlarged view, in front elevation, showing the feeding and gaging members in proper relation to a workpiece for cutting an abrupt scarf; and

Fig. 8 is a detail in elevation showing the positions of the work-engaging parts for cutting a shoulder or fold scarf;

Fig. 9 is a section of a work piece showing the shoulder or fold scarf which is produced when

the work engaging parts are in the positions shown in Fig. 8;

Fig. 10 is a detail in elevation showing the positions of the work-engaging parts for cutting a narrow seam scarf;

Fig. 11 is a section of a work piece showing the narrow seam scarf which is produced when the work-engaging parts are in the positions shown in Fig. 10;

Fig. 12 is a detail in elevation showing the positions of the work-engaging parts for cutting a feather edge scarf;

Fig. 13 is a section of a work piece showing the feather edge scarf which is produced when the work-engaging parts are in the positions shown in Fig. 12;

Fig. 14 is a detail in elevation showing the positions of the work-engaging parts for cutting an abrupt scarf to prepare the edge for searing or heat turning; and

Fig. 15 is a section of a work piece showing the abrupt scarf which is produced when the work-engaging parts are in the positions shown in Fig. 14.

The illustrated machine is similar in many respects to the machine disclosed in Letters Patent No. 2,134,809 abovementioned. The present machine like that of said patent comprises a rotary disk knife 10, a rotary feed roll 12, and a rotary feed disk 14. The knife is manually adjustable in the direction of its axis toward and from the feed roll, the axis of the knife being inclined slightly from the vertical. The feed disk of the illustrated machine, while rotating idly, cooperates with the feed roll by pressing the work against it. The feed roll shaft is rotatable in a block 16 which is adjustable on a support 18 in a direction which is axial of the feed roll, said support being angularly adjustable in an arcuate guideway 20 the center of curvature of which lies in a horizontal axis. Axial adjustment of the feed roll enables the feed roll to be shifted to the right or left relatively to the center of the arcuate guideway 20. The axis about which the support 18 is angularly adjustable passes at right angles through an element in the upper surface of the feed wheel for any normal position of axial adjustment of the feed wheel. The support 18 carries a superstructure by which the feed disk is carried so that angular adjustment of the feed roll support adjusts the feed disk. The curved guideway 20, in which the feed roll support is adjusted, is located at the outer end of a head 22, said head being angularly adjustable in a horizontal path about the

55

axis of a vertical stud 24 to adjust the feed roll toward and from the knife, and the feed roll shaft is connected by a telescoping shaft and universal joints with a driving pulley 26. The head 22 is supported upon a base 28 which is clamped upon a work bench 30. The feed roll support 18 is connected by a link 32 with a treadle-controlled arm 34 pivoted to the base of the machine, said arm carrying a small pivotally mounted block 35. Threaded on a small horizontal rod 36 are two adjustable nuts 38, 40 which engage the pivotally mounted block to limit rocking movement of the arm 34, and, hence, the extent of angular adjustment of the feed roll support. The arm is connected by a link and a pivot with the upper end of a treadle rod 42 in such manner that vertical movement of the treadle rod swings the arm to the right or left. The lower end of the rod is connected to a treadle 44 normally held in raised position by a spring 46, to hold the feed roll in its up position (in which the uppermost element of its periphery forms a small angle with the plane of the knife or is substantially parallel thereto).

The elements so far described which are substantially like corresponding elements of the machine disclosed in Letters Patent No. 2,134,809 are as follows: the knife 10 with its provisions for mounting, driving and adjusting; the provisions for mounting and driving the feed roll 12; the arrangement for axially adjusting the feed roll block 16 in its support 18; and the arrangements for tilting the feed mechanism, including the arcuate guideway 20 and the mechanism operated by the treadle 44. A more complete disclosure of some of these elements may be found in United States Letters Patent No. 1,866,918, granted July 12, 1932 upon the application of Milton H. Ballard.

An edge guide 48 is carried indirectly by the block 16 which carries also a yieldingly mounted presser 50. The presser and edge guide are mounted for quick adjustment in a path transverse to the line of feed of the work by manipulation of a treadle 52. The presser and edge guide may be substantially like the presser and guide disclosed in U. S. Letters Patent No. 1,180,222, granted April 18, 1916, upon an application filed in the name of Alexander M. Alexander. The presser yields upwardly from a stop position adjustably determined by a screw 53 (Figs. 2 and 3). The mounting of the presser and edge guide including the mechanism which causes them to be adjusted horizontally when either or both of the treadles 44, 52 are manipulated is somewhat like that of the machine disclosed in Letters Patent No. 2,134,809, already mentioned. Although the details of the somewhat different construction disclosed herein form no part of the present invention, they will be briefly described.

The edge guide 48 is integral with a slide 54 (Figs. 2 and 3) which also carries the presser 50. The slide 54 is slidably mounted in a block 56 which is secured by an adjustable connection 58 (more fully described in Letters Patent No. 1,866,918, above-mentioned) to a bracket 60 (Fig. 1) secured upon an extension of the block 16. The edge guide carrier slide 54 is normally maintained in a desired position of adjustment by a coiled compression spring 62 interposed between the slide 54 and a lug 64 on the block 56. The spring 62 tends to urge the edge guide carrier slide 54 outwardly or toward the left, as viewed in Figs. 1 and 2, as far as is permitted by a crank

arm 66 (Fig. 3) having a rounded end portion which engages a groove 68 in the carrier slide. The arm 66 is secured upon a shaft 70 which is freely rotatable in a bearing formed in the block 56. Extending from the shaft 70 is a second crank arm 72 upon which is pivotally mounted the upper end of a depending rod 74. For guiding the rod 74 there is provided a bearing block 76 which is pivotally mounted upon the block 56 and which thus acts as a swivel bearing. The lower end of the rod 74 engages an abutment 78 (Fig. 1) carried by the upper end of a slide 80, and may be raised or lowered to any desired position of adjustment by means of a screw 82 threaded into the lower end of the slide and having a knurled head 84 to facilitate turning. A guideway for the slide 80 is carried by the head 22. Axial movement of the screw 84 is prevented by a pair of lugs 83 secured upon the head 22 and engaging a groove formed in the head of the screw.

The treadle 52, by which the operator is enabled to shift the position of the edge guide in the course of operation, is connected to the slide 54 by a cable 90 protected by a sheath 92. Depression of the treadle 52 will move the edge guide against the compression of the spring 62, such movement being freely permitted since the rod 74 rises out of contact with the abutment 78. The extent to which the edge guide may thus be moved is adjustably determined by a screw 94 threaded into the block 56 and engageable with a pin 96 secured in a lug on the slide 54. For limiting the extent to which adjustment may be made in the opposite direction, a second screw 98 is provided. For some operations, as will later be pointed out, the screw 98 is turned to an inoperative position, and for other operations it is adjusted to limit the outward movement of the edge guide to an extent less than permitted by the abutment 78.

The machine as so far described, except for the changes above pointed out, may be substantially in accordance with the disclosures of the several patents above-mentioned.

The feed disk 14 of the machine illustrated herein is mounted to yield in a direction normal to its axis rather than axially as in previous machines. The disk (Figs. 4, 5 and 6) is carried upon the lower end of a shaft 100 which rotates idly in a block 102, although, if desired, the shaft 100 may be driven by a belt or by any suitable type of gearing. Parallel to the shaft 100 is a stationary shaft 104 upon which the block 102 is rotatably mounted. Secured upon the stationary shaft 104 is a collar 106 from which extends a lug 108 having its outer portion turned downwardly. A rod 110 fixed at one end to the downwardly turned portion of the lug 108 extends in a substantially horizontal direction through an opening in the block 102 between the shafts 100 and 104. The outer end portion of the rod 110 is threaded and carries a nut 112. Surrounding the rod 110 and interposed between the nut 112 and a bearing surface formed on the block 102 is a coil compression spring 114, which tends to rotate the block 102 in a clockwise direction, as viewed in Fig. 5, about the shaft 104. The effect of the spring is therefore to urge the feed disk to the right, as viewed in Fig. 1. The compression of the spring may be adjusted by turning the nut 112. Rotation of the block 102 about the shaft 104 is limited by an upright pin 116 secured in the block 102 and extending upwardly into an arcuate slot formed

in the stationary collar 106. The upper portion of the shaft 104 is clamped by screws 118 in a split block 120. Heightwise adjustment of the feed disk 14 relatively to the feed roll 12 is effected by moving the shaft 104 up or down in the block 120 to the desired position before tightening the screws 118. Adjustment of the stop position of the disk 14 under the influence of the spring 114 is likewise effected by turning the shaft 104 in the block 120 before tightening the screws 118. Extending substantially horizontally from an upper portion of the block 120 is a supporting stem 122 which is slidably mounted in a bracket 124 carried by the bracket 60. The stem 122 is clamped in the bracket in a desired position of adjustment to provide suitable clearance between the feed disk 14 and the feed roll 12. A second stem 126 extending from the block 120 parallel to the stem 122 is slidable in the bracket 124 to prevent rotation of the block 120 about the stem 122.

It will be observed that the above-described arrangement for mounting the feed disk enables the feed disk to yield in accordance with varying thicknesses of the work. Such yielding, moreover, takes place in a plane normal to the feed disk away from the feed roll and away from the axis of the knife. Therefore, however close the knife and the feed disk may be adjusted to each other, there is no danger of the work-piece by reason of its thickness causing the feed disk to jam up against the knife. Such mounting of the feed disk thus permits the close adjustment of the knife and the feed disk so desirable in many types of work.

The feed roll 12 differs from the feed rolls disclosed in the patents above-mentioned by reason of the fact that it has a knurled cylindrical work-engaging surface 128 and a smooth frusto-conical work-engaging surface 130. The portion 130 converges from the diameter of the portion 128 to a smaller diameter. The feed disk 14 has a plane upper surface and a downwardly converging frusto-conical work-engaging edge portion. The angle of the elements of the surface 130 to the axis of the feed roll is complementary to the angle of the elements of the feed disk 14 with the axis of the feed disk; that is, the sum of the two angles is 90°. If a section be taken through the axes of the feed roll and the feed disk, the adjacent elements of said members will be parallel.

In the operation of the machine, the feed roll 12 is driven in a direction to feed a work-piece W (Fig. 2) away from the operator. The work-piece is presented with its edge against the edge guide 48; its marginal portion is held against the cylindrical portion 128 of the feed roll 12 by the presser 50. The feed disk 14, under the influence of the spring 114 urging it toward the right, holds the work-piece in driving engagement with the conical portion 130 of the feed roll. The feed roll will be considered for the present to have been adjusted axially in the block 16 to bring the mid-point (indicated by X on Fig. 8) of its work-engaging surface about into register with the center of the arcuate guideway 20.

The machine is shown in Fig. 1 with the treadles 44 and 52 both up. The feed roll and feed disk assembly is maintained in a position of angular adjustment determined by the block 35 bearing against the nut 38 under the influence of the spring 46. The nut 38 has been turned to such a position as to cause the upper surface of

the feed disk 14 and the uppermost element of the cylindrical surface 128 to lie in a plane parallel to the plane of the cutting edge of the knife 10. The knife, the plane of which is indicated by the reference character K in Fig. 8, is adjusted to a height above the feed roll equal to half the thickness of the workpiece. The edge guide 48 is maintained in a position of adjustment determined by the rod 74 in engagement with the abutment 78 under the influence of the spring 62. When thus adjusted, as shown in Figs. 1 and 8, the machine will cut a shoulder or fold scarf of the type shown in Fig. 9. This scarf will be relatively narrow, its width depending upon the adjustment of the abutment 78. Wider scarfs of this type may readily be obtained without changing the adjustment of the abutment 78, merely by depressing the treadle 52 to move the edge guide toward the right to a stop position determined by the screw 94.

The work-engaging parts may be instantly changed from the positions shown in Figs. 1 and 8 to positions which will cause the machine to produce a narrow seam scarf of the type disclosed in Fig. 11. This is accomplished merely by depressing the treadle 44 to rotate the feed disk and feed roll assembly counterclockwise (as viewed in Fig. 1) to a position determined by engagement of the block 35 with the nut 40. As the assembly thus rotates, the rod 74 rises relatively to the abutment 78, enabling the crank arm 72 to rotate in a clockwise direction (as viewed in Fig. 1) while the spring 62 pushes the edge guide carrier to the left. The several parts of the machine will thus be brought into the positions shown in Figs. 2 and 10, in which the plane of the cutting edge of the knife 10 is indicated by the reference character K. A wider seam scarf may be obtained, without changing the adjustment of the abutment 78, by turning the screw 98 (which hitherto has occupied an out-of-the-way position) to a position to cause it to engage the pin 96 before the feed disk and feed roll assembly reaches its limiting position. A still wider seam scarf may be obtained by depressing the treadle 52 as well as the treadle 44, thereby moving the edge guide toward the right to a stop position determined by the screw 94. To obtain a feather edge scarf, such as is shown in Fig. 13, both treadles are depressed, the screw 94 being adjusted far enough to the right to bring the edge guide into register with the right-hand edge of the cylindrical portion 128 of the feed roll, as shown in Fig. 12.

It is sometimes desirable to produce a more abrupt scarf than can be obtained by angular adjustment of the feed roll and feed disk assembly. Such an abrupt scarf (shown in Fig. 15) is necessary to prepare the edge for searing, or heat turning, as the operation is sometimes called. To form a scarf of this character on the illustrated machine, the several work-engaging parts are adjusted to the positions shown in Figs. 7 and 14. The nut 38 is adjusted to the position shown in Fig. 1 to bring the plane of the upper surface of the feed disk 14 and the uppermost element of the cylindrical surface 128 parallel to the plane K of the cutting edge of the knife, with the treadle 44 up. For convenience of illustration the plane K is shown in Fig. 7 as horizontal, but actually it is tilted as shown in Fig. 14. The edge guide 48 is then adjusted to the left, by turning the screw 82, almost to the edge of the feed roll which separates the conical surface 130 from the cylindrical surface

128. The knife 10 is then adjusted downwardly to bring the plane K of its cutting edge almost into engagement with the upper surface of the feed disk 14 and the uppermost element of the cylindrical surface 128. The angle of the resulting bevel, which should be accurately maintained in this type of work, is thus determined by the angle of the conical surface 130 and not by the amount of tilt of the feed roll and feed disk assembly.

The abrupt scarf above-mentioned is usually formed on work-pieces other portions of which require also a seam scarf or a feather scarf, and but rarely on work-pieces calling for a fold scarf. To avoid unnecessary heightwise adjustment of the knife when passing from an abrupt scarf to a seam scarf or a feather scarf, or vice versa, the feed roll may be adjusted axially to bring its right-hand edge into register with the center of the arcuate guideway 20, rather than in the position shown in Fig. 8, which is to the right of the center. The knife may then remain in its downward position of adjustment, almost in contact with the feed disk and the feed roll. With the machine thus adjusted, a seam scarf or a feather scarf may be produced upon the same work-piece as an abrupt scarf merely by depressing both treadles, the retracted position of the edge guide being determined by the stop screw 94.

Having described my invention, what I claim as new and desire to secure by Letters Patent of the United States is:

1. A skiving machine having, in combination, a knife, a feed roll, a feed disk for holding work against said feed roll, a support for said feed disk pivotally mounted for swinging movement about an axis parallel to the axis of the feed disk, and a spring for yieldingly urging the feed disk toward the feed roll to cause the feed disk to grip the work against the feed roll.

2. A skiving machine having, in combination, a knife, a feed roll, a pair of rotary feed members arranged with their axes substantially at right angles to each other, said feed members having conical work-engaging surfaces, and a support for one of said feed members constructed and arranged to yield in a direction normal to the axis of that feed member.

3. A skiving machine having, in combination, a knife, a pair of rotary feed members arranged with their axes substantially at right angles to each other, said feed members having work-engaging surfaces defined by cones the vertex angles of which are supplemental, and a support for one of said feed members constructed and arranged to yield in a direction normal to the axis of that feed member.

4. A skiving machine having, in combination, a knife, a feed roll having a cylindrical portion and a frusto-conical portion converging from said cylindrical portion, a feed disk having a frusto-conical work-engaging surface, a support constructed and arranged to enable said feed disk to move in a direction normal to the axis of the feed disk, and a spring acting upon said disk to cause the disk to press the work in said direction against the frusto-conical portion of the feed roll.

5. A skiving machine having, in combination, a rotary disk knife, a feed roll having a work-engaging surface part of which is cylindrical and part of which is conical, a feed disk having

a conical work-engaging surface, a spring for urging the feed disk toward the feed roll in a path normal to the axis of the feed disk to cause the work to be gripped between the two conical surfaces, and a presser for holding the work against the cylindrical surface of the feed roll.

6. In a skiving machine, a feed roll, a disk having a conical work-engaging edge, a block in which said disk is journaled for rotation, a support upon which said block is mounted for swinging movement about an axis parallel to the axis of the disk, a spring interposed between said support and said block for swinging the block to cause the disk to press a work-piece against the feed roll, a stop on said support for limiting the approach of the disk toward the feed roll under the influence of said spring, said support being angularly adjustable about the axis of swinging movement of the block to adjust the position of said stop, and means for securing the support in angularly adjusted position.

7. A skiving machine having, in combination, a rotary disk knife, a rotary feed roll located beneath the knife and having an outer end of reduced diameter, a rotary feed disk located below the plane of the cutting edge of the knife and arranged to cooperate with the portion of reduced diameter of the roll to grip the work and to aid the roll in advancing the work to the knife, and a support for the feed disk yieldingly mounted for movement in a direction substantially normal to the axis of rotation of the feed disk to accommodate variations in thickness of the work.

8. A skiving machine having, in combination, a knife, a feed roll having a cylindrical portion and a frusto-conical portion converging from said cylindrical portion, a feed disk having a frusto-conical work-engaging surface, a support constructed and arranged to enable said feed disk to move in a direction normal to the axis of the feed disk, a spring acting upon said disk to cause the disk to press the work in said direction against the frusto-conical portion of the feed roll, means for adjusting the feed roll and feed disk angularly in unison, an edge gage, and means for adjusting the edge gage longitudinally of the feed roll.

9. A skiving machine having, in combination, a knife, a feed roll having a cylindrical portion and a frusto-conical portion converging from said cylindrical portion, a feed disk having a frusto-conical work-engaging surface, a support constructed and arranged to enable said feed disk to move in a direction normal to the axis of the feed disk, a spring acting upon said disk to cause the disk to press the work in said direction against the frusto-conical portion of the feed roll, means for adjusting the feed roll and feed disk angularly in unison to cause the uppermost element of the cylindrical portion of the feed roll to be substantially parallel to the plane of the knife, an edge gage, and means for adjusting the gage lengthwise of the feed roll into a position in which the work-engaging face is adjacent to the junction of the cylindrical and conical surfaces of the feed roll, whereby an abrupt scarf may be formed upon the edge of the work preparatory to subjecting it to a searing operation.

PAUL H. DIXON.
